UNITED STATES PATENT OFFICE.

JOHN SHANKS AND HENRY SIMPSON, OF BARRHEAD, SCOTLAND.

LAVATORY OR URINAL.

SPECIFICATION forming part of Letters Patent No. 690,326, dated December 31, 1901.

Application filed October 15, 1901. Serial No. 78,714. (No model.)

To all whom it may concern:

Be it known that we, JOHN SHANKS and HENRY SIMPSON, subjects of the King of Great Britain and Ireland, and residents of Barrhead, in the county of Renfrew, Scotland, (whose postal address is Tubal Works, Barrhead, Scotland,) have invented certain Improvements in Lavatories or Urinals, of which the following is a specification.

10 Our said invention relates to what are known as "folding-up" lavatories, principally used on board ship and in railway-carriages, and to urinals of the class having separate basins fixed to a slab or post forming the back of the urinal.

Our invention has for its object to improve the method of securing the basins used in such lavatories and urinals so that not only will the basins be held in place in a satisfactory manner, but also so that the basins can be readily detached for the purpose of cleaning away any impurities which may have gathered between them and their supports.

In folding-up lavatories as hitherto generally constructed the basin is made with a sole, which is fixed by screws to a tray or base hinged to the cabinet forming the lavatory. The basin when attached in this way becomes practically a fixture, as the work of 25 detaching it afterward is found to be difficult and tedious. Water and impurities gather in course of time between the under side of the basin and the tray; but as the basin cannot be raised conveniently to enable the impurities 30 to be removed the result is that the lavatory soon becomes foul and malodorous. These defects and disadvantages are, however, overcome by our improved method of securing the basin to the tray.

40 The basin according to our invention is formed with a snug or snugs arranged to engage in a socket or sockets on the tray, a fastening-bolt hinged on the tray being arranged to engage in a slotted snug on the basin, a thumb screw or nut on the bolt being thereafter tightened up, so as to hold the basin securely against the tray, or any other equivalent fastening device may be employed. The basin can thus be easily detached for 45 cleaning purposes by simply slackening the thumb-screw and then withdrawing the snug parts of the basin from the socket parts of

the tray. In some cases the fastening-bolt may be dispensed with.

A modification of the hereinbefore-described 55 fixing arrangement for lavatory-basins is employed for securing urinal-basins to the back slab of the urinal.

In order that our said invention and the manner of performing the same may be properly understood, we hereunto append two sheets of explanatory drawings, to be herein-after referred to in describing the improvements.

Figures 1, 2, and 3 on Sheet 1 of the drawings are respectively a longitudinal section, an inverted plan, and a back elevation of a folding-up lavatory provided with the improved fixing arrangements. Figs. 4 and 5 are respectively a transverse section and an 70 inverted plan of a similar lavatory provided with a variation of the improvements. Fig. 6, Sheet 2, is a plan, and Fig. 7 a back elevation, of a lavatory, showing another variation of the improved parts, Fig. 8 being a vertical 75 section of a portion of the basin and showing a special part of the improvements. Fig. 9 is a back elevation, and Fig. 10 a horizontal section, of a urinal-basin and showing the improved fixing parts applied thereto. 80

According to the invention, as shown in Figs. 1, 2, and 3, a snug or holding-piece A is formed on the under side of the lavatory-basin B at the back, the snug projecting out backward from the basin-sole B' and engaging in a socket-piece or metal eye C, preferably lined with rubber C', and attached to the tray D by ordinary fixing-screws C². Another snug or flange projection E, having a long open central slot E', is formed on the 90 front of the basin B, a screw-bolt E², hinged to a pivot-piece G, fixed to the tray D, being arranged to engage in the slot, the bolt being provided with a thumb-screw or nut E³. The basin B is shown in its fixed position on the 95 tray D, and when in this position the back snug A engages in the socket C and the hinged bolt E² in the slot E' in the front snug E, the basin being held firmly in position by tightening the thumb-screw E³ down upon the angular face E⁴ of the front snug E, a rubber washer E⁵ being preferably interposed between the thumb-screw and the snug. The basin B can be easily detached from the tray 100

D by simply slackening the thumb-screw E³ sufficiently, so as to allow the hinged bolt E² to be turned down, thereby permitting the back snug A to be withdrawn from its socket C, and thus releasing the basin, as desired.

If preferred, two snugs A' A², as shown in dotted lines in Fig. 2, may be substituted for the single snug A, sockets being arranged on the tray D to suit, or the single snug A may 10 be placed at the side of the basin B instead of at the back, the slotted snug E being then placed opposite to it.

As shown in Figs. 4 and 5, a downwardly-projecting central snug H, made with inclined 15 and wedge-shaped sides, is formed on the under side of the basin B, the snug engaging in a counterpart socket J, arranged on the surface of the tray D. The socket J consists, preferably, of two flanged pieces J' J², which 20 are fixed opposite each other and shaped and set on the tray D so that when the basin B is in its fixed position, Fig. 4, their upwardly-projecting flanges J³ bear against the sides of the snug H, and thus form a dovetailed- 25 joint connection between the parts. Rubber packing J⁴ is preferably interposed between the flanges J³ and the sides of the snug H. The hinged bolt-fastening arrangement previously described may be employed if desired.

30 In Figs. 6, 7, and 8 two inclined side parts K' K² are formed on the basin B near the outer edge of the basin-sole B', the sides being shaped similarly to the sides of the central snug H of the previous example. When the 35 basin B is in its fixed position, Fig. 6, the inclined side parts K' K² engage between corresponding flanged pieces L' L², as in the previous modification, so that a firm but simply-disconnected dovetail joint is formed, as before. The flanged pieces L' L² are fixed to 40 the surface of the tray D by screws L³, as shown in Fig. 8, which is a vertical section of the basin B at the dotted line M N, Fig. 6, so as to show clearly an inclined side part K² 45 in contact with its corresponding flange-piece L². The hinged bolt E², working in the slotted snug E, and the thumb-screw fastener E³ are preferably employed in connection with this example.

50 In applying our invention to urinal-basins instead of securing such basins to the back

slabs or bases by exposed outer lugs or by projecting parts formed or fixed on them and inserted in holes in the slabs we fix them by a dovetail-joint arrangement similar to that 55 described and shown in connection with Figs. 4 and 5 and which is clearly indicated in Figs. 9 and 10. Within the back rim or fitting edge P of the basin Q, which bears against the back slab R, a central snug S is formed 60 on the back wall Q' of the basin, the snug projecting backward toward the slab and being formed with inclined and wedge-shaped sides, which are arranged to fit between corresponding flange-shaped pieces S' S², fixed 65 to the slab. When the basin Q is in its fixed position, as shown, the snug S engages in the socket composed of the two flanged pieces S' S², and thereby forms the dovetail-joint fixing, as required. The central snug S is kept 70 clear of the back slab R, so as to facilitate the close fitting of the rim or edge P against the slab, and thus lessen the possibility of water and impurities lodging between the back of the basin and the slab. 75

What we claim as our invention is—

1. In lavatories, a basin, a tray to which it is secured, sockets on the upper face of the tray, snugs on the lower part of the basin and a bolt secured to the tray on its upper face 80 to hold the snugs firmly in the sockets, as and for the purpose described.

2. A basin having snugs on the bottom and a flanged part in combination with a tray having sockets and a fastening-bolt on its 85 upper face, said snugs fitting into the sockets and said bolt holding the basin to the tray through the flange, substantially as described.

3. A basin having a snug on the bottom with wedge-shaped and inclined sides, a flange 90 on the basin, a tray having a socket for the snug and a bolt on its upper face to engage the flange on the basin, substantially as described.

In testimony whereof we have signed our 95 names to this specification in the presence of two subscribing witnesses.

JOHN SHANKS.
HENRY SIMPSON.
